UNITED STATES PATENT OFFICE

FRANCIS E. KERSEY, OF LEBANON, INDIANA

MUFFLER

Application filed September 25, 1930. Serial No. 484,431.

This invention relates to a muffler adapted for use with the exhaust of an internal combustion engine. The object of the invention is to provide a device which will not only muffle the sound of the exhaust but which will offer very little back pressure to reduce the power of the automobile and which will respond to relieve excessive pressure without injury to the muffler in the case of back-fire, all as will be more particularly pointed out hereinafter and claimed.

Referring to the accompanying drawings, which are made a part hereof and on which similar reference characters indicate similar parts,

Figure 1 is a longitudinal section illustrating one form of the invention,

Figure 2, a section on line 2—2 of Figure 1, and

Figure 3, a section on line 3—3 of Figure 1.

In the drawings reference character 10 indicates a casing, here shown as cylindrical but which may be made in any suitable form. The casing is provided with end plates 11 and 12, here shown as fitted within the ends of the casing but which may be secured in any suitable way or made integral with the casing.

A pair of axially aligned pipes 13 and 14 are positioned centrally of the casing 10. The pipe 13 forms the inlet for gases and the pipe 14 the outlet from the muffler. The pipes 13 and 14 are joined together at their inner ends to a plate 15, here shown as a square plate having its corners 16 secured within the casing. The plate is provided with a number of perforations 17. The inlet pipe 13 likewise is provided with a number of openings 18 through which exhaust gases from the engine pass into the body of the casing 10.

Corresponding openings 19 are provided in the outlet pipe 14 through which exhaust gases pass into the atmosphere. The outlet pipe 14 is also provided with a series of elongated outlet openings 20. These openings are preferably tapered with the wider end

extending toward the direction of flow of the outlet gases. Surrounding the outlet pipe 14 is a cylindrical sleeve 21 to which is attached a disk 22 which fits within the casing 10. The disk 22 of course, if desired, may be made integral with the sleeve 21. Positioned at the rear of the disk 22 and between it and the end plate 12 is a compression spring 23. The sleeve 21 is positioned so as to cover up a portion of the length of the openings 20 in the pipe 14. From the drawings it will be seen that axial movement of the disk 22 will vary the size of openings through the slots 20 in to the exhaust pipe 14.

In operation the exhaust gases from the engine enter the pipe 13 and pass out through the openings 18. The plate 15 preventing their passage directly into the pipe 14. These gases impinge against the inner walls of the casing by which their velocity is decreased and by means of which the noise is muffled. The gases then pass around the outer edge of the plate 15 and through the opening 17 by means of which they are further retarded so as to further muffle any sounds which would be produced by them. The gases then issue through the ports 19 into the outlet pipe 14 through which they pass to the atmosphere. In entering the casing 10 at the right of the plate 15 they also impinge against the plate 22 by means of which their velocity is also retarded. In case of an excessive volume of exhaust gases or in case some combustible gases pass from the engine and explode in the muffler the high pressure created thereby is relieved by means of the spring 23 which yields and permits the disk 22 to move axially of the pipe 14 and to uncover more of the openings 20. This relieves pressure in the muffler without any damage to it and likewise muffles the sound so as to insure a quiet smooth running of the engine without any unnecessary high pressure built up in the muffler to reduce the power of the engine.

It will be obvious to those skilled in the art that various changes may be made in my device without departing from the spirit of the invention and therefore I do not limit myself to what is shown in the drawings and described in the specification, but only as indicated in the appended claims.

Having thus fully described my said invention, what I claim as new and desire to secure by Letters Patent, is:

1. A muffler comprising a cylindrical casing, a pipe extending through one end of the casing and terminating near the front end of said casing, a disk closing the end of the said pipe, a second pipe secured to the said disk and extending through the other end of the casing, said pipes being provided with openings for permitting the passage of the products of combustion, a flanged sleeve 20 surrounding the said second pipe, spring means tending to hold the said flanged sleeve resiliently against the pressure of exhaust gases in the casing, and over said openings in the said second pipe, said openings being controlled by the said sleeve, substantially as set forth.

2. A muffler comprising a casing, a pair of aligned pipes of a substantially uniform diameter positioned axially of the casing, a disk positioned between the inner ends of said pipes, so as to close passage from one to the other, said disk being connected to the interior of the said casing and provided with a plurality of openings therethrough, said pipes also being provided with a plurality of elongated axially extending openings, said openings providing passage for exhaust gases from an engine, a flanged sleeve slidably mounted on one of said pipes and adapted to 40 control the size of some of said openings, and a spring against which said flanged sleeve seats, said spring yielding in response to explosions in said casing or to abnormal high pressures in said casing to increase the size of the exhaust openings, substantially as set forth.

3. A muffler comprising a casing, a pipe extending axially through said casing, said pipe having a plate separating it into inlet 50 and outlet portions, each portion of said pipe having elongated openings to provide outlets from and into said pipe, and means resiliently mounted on said outlet portion of said pipe and yieldable under predetermined high pressure in said casing to increase the size of the outlet openings into said pipe, substantially as set forth.

4. A muffler comprising a casing, a pipe extending axially through said casing, a plate 60 dividing said pipe into inlet and outlet portions, each portion of said pipe being provided with a plurality of openings, a sleeve mounted on said outlet portion normally covering a part of said openings therein, said sleeve being further provided with a plate ex-

tending to the side of said casing and resilient means mounted between said plate and an end of said casing for holding said sleeve in position yet yieldable in response to explosions or abnormal high pressures in said casing to increase the size of outlet opening thereby preventing injury to said muffler, substantially as set forth.

In witness whereof I have hereunto set my hand at Indianapolis, Indiana, this 23d day of September, A. D. nineteen hundred and thirty.

FRANCIS E. KERSEY.
